UNITED STATES PATENT OFFICE.

JEFFERSON D. McCABE, OF WOODBURY, TENNESSEE.

DESIGN FOR A WAGON-BODY BRACE.

SPECIFICATION forming part of Design No. 33,434, dated October 23, 1900.

Application filed September 29, 1900. Serial No. 31,583. Term of patent 14 years.

To all whom it may concern:

Be it known that I, JEFFERSON D. McCABE, a citizen of the United States, residing at Woodbury, in the county of Cannon and State 5 of Tennessee, have invented and produced a new and original Design for a Wagon-Body Brace, of which the following is a specification.

The invention relates to a new and original 10 design for a wagon-body brace; and it has for its object to provide a design of this character which will be both ornamental and useful.

The leading feature of the design consists 15 in the design forming the subject-matter of the accompanying illustration.

In the drawings, Figure 1 is a perspective view of a wagon-body brace, showing my new and original design. Fig. 2 is a horizontal 20 sectional view of the same, illustrating the form of the bottom socket.

Referring to the drawings, 1 designates a wagon-body brace, consisting of a vertical body portion provided at intervals with openings 25 2 and having segmental enlargements at opposite sides, forming intermediate circular portions 3, which have their peripheral edges

arranged concentric with the adjacent openings 2. The top of the body portion of the brace is provided with a circular enlargement 30 or head 4, which has a periphery concentric with the adjacent opening. The lower end of the body portion of the brace is provided with a socket 5, having a polygonal exterior and a circular interior. The socket, which 35 is provided with straight sides, has its corners truncated to form narrow vertical faces or panels 6. The socket is provided with a circular opening 7, and it has tapering upwardly-extending curved webs 8, presenting 40 a concave inner face, which is concentric with the circular opening 7. The outer faces of the flanges form continuations of the adjacent side faces of the socket.

What I claim is—

The design for a wagon-body brace herein 45 shown and described.

In testimony that I claim the foregoing as my own I have hereto affixed my signature in the presence of two witnesses.

JEFF. D. McCABE.
